CLAIM

The ornamental design for a door mat base plate or similar article, as shown and described.

DESCRIPTION

FIG. 1 is a top plan view of a door mat base plate or similar article showing our new design;

FIG. 2 is a front elevational view thereof;

FIG. 3 is a bottom plan view thereof;

FIG. 4 is a left side elevational view thereof;

FIG. 5 is a fragmentary vertical sectional view thereof on a larger scale, taken on line 5—5 of FIG. 1;

FIG. 6 is a fragmentary rear elevational view thereof, on the same scale as FIG. 5; and

FIG. 7 is a fragmentary top plan view thereof, on the same scale as FIG. 5.

The right side and rear thereof are mirror images of the left side and front thereof, respectively.

FIG. 1

FIG. 2

FIG. 3

FIG. 4
